(57) **CLAIM**

The ornamental design for an automotive roof, as shown and described.

DESCRIPTION

FIG. 1 is a rear end/right side perspective view of an automotive roof in accordance with the present invention; FIG. 2 is a right side/front end perspective view of the automotive roof of FIG. 1;

FIG. 3 is a front end elevation of the automotive roof of FIG. 1;

FIG. 4 is a front end/left side perspective view of the automotive roof of FIG. 1;

FIG. 5 is a left side/rear end perspective view of the automotive roof of FIG. 1; and,

FIG. 6 is a rear end elevation view of the automotive roof of FIG. 1.

The broken lines are for illustrative purposes only and form no part of the claimed design.
